UNITED STATES PATENT OFFICE.

CHARLES H. FALLS, OF NASHUA, IOWA.

BRIDLE-BIT.

1,178,998.

Specification of Letters Patent. Patented Apr. 11, 1916.

Application filed May 22, 1915. Serial No. 29,827.

To all whom it may concern:

Be it known that I, CHARLES H. FALLS, a citizen of the United States, residing at Nashua, in the county of Chickasaw and 5 State of Iowa, have invented certain new and useful Improvements in Bridle-Bits; and I do hereby declare the following to be a full, clear, and exact description of the invention, such as will enable others skilled 10 in the art to which it appertains to make and use the same, reference being had to the accompanying drawings, and to the letters and figures of reference marked thereon, which form a part of this specification.

15 This invention relates to new and useful improvements in bridle bits and the object in view is to generally improve upon and render more efficient devices of this nature and consists essentially in a frictionless bit, 20 having various details of construction, combinations and arrangements of parts which will be hereinafter fully described, shown in the accompanying drawings and then specifically defined in the appended claims.

25 My invention is illustrated in the accompanying drawings, in which:

Figure 1 is a perspective view of a bit embodying the features of my invention. Fig. 2 is a central longitudinal sectional 30 view through the same.

Reference now being had to the details of the drawings by letter, A designates a snaffle from which a rod B projects, the inner face of the snaffle about said rod being 35 recessed as at C. The cheek piece or button D has a boss D' projecting from the outer face thereof and adapted to engage and turn in said recess and has a hollow tubular portion E, shouldered as at E', and one end 40 F is reduced as shown and over which tube a covering of leather H, or other suitable material, is placed. A second button, designated by letter N, has a central opening O and the inner convexed surface of the 45 button N has a flaring bushing Q, adapted to fit over the reduced end of the tubular portion and over which one end of the leather covering passes.

It will be noted that the bushing R projecting from the outer face of the button N has its end flush with the end of the contracted part of the tubular portion and is adapted to engage a recess S formed in the inner face of the snaffle T, the said recess 55 having a threaded aperture in its bottom

for the reception of the threaded end of said rod. A suitable washer J is interposed between the bushing R and the wall of the recess provided for its reception.

Each button has an elongated loop K projecting from the edge thereof and a smaller loop K', spaced apart, and a cheek strap K² is adapted to be fastened to each loop K, while a connecting strap K³ is adapted to pass underneath the jaw of the animal and is connected at its ends to the strap K². When the cheek and connecting straps are fastened as shown, it will be noted that the tubular portion will be practically stationary in the animal's mouth, while the bit 70 rod is adapted to turn axially within the tubular portion, making an ideal driving bit for track use, also by the employment of the connecting strap the bit may be used for any kind of snaffle. 75

What I claim to be new is:

1. A bit comprising snaffles recessed upon the inner faces thereof, a rod projecting from the bottom of the recess in one snaffle, a cheekpiece having an integral tubular projection upon its inner face mounted upon said rod, the other snaffle having a threaded aperture with which the end of said rod engages, a second cheekpiece journaled on the end of said tubular projection and having 80 a boss upon its outer face engaging a recess in the last mentioned snaffle, and a covering 85 for said tubular projection.

2. A bit comprising snaffles, recessed upon the inner faces thereof, a rod having a threaded end and secured to one snaffle and projecting from the recess therein, a cheek piece having a boss upon the outer face thereof and journaled in a recess in the snaffle and having a tubular portion 90 projecting from its inner concaved face, said tube having a reduced portion, a second cheek piece having bosses upon the opposite faces thereof and adapted to fit over said reduced portion of the tube, the second snaffle 95 being fitted about a central aperture therein adapted to engage the threaded end of the rod and provided with a recess for the reception of the boss upon the outer face of the adjacent cheek piece, and a leather 100 covering for said tubular portion.

3. A bit comprising snaffles, recessed upon the inner faces thereof, a rod secured to one snaffle and projecting from the recess therein, cheek pieces provided with loops and 110

having bosses upon the outer faces thereof, journaled in the recesses of said snaffles, a covering for said rod, cheek straps for attachment to corresponding loops upon the cheek pieces, and a connecting strap fastened to other corresponding loops upon the cheek pieces.

In testimony whereof I hereunto affix my signature in presence of two witnesses.

CHARLES H. FALLS.
